UNITED STATES PATENT OFFICE

168,219

RAILWAY OBSERVATION CAR BODY

Alfred B. Girardy, Park Forest, Donald W. Doman, Harvey, and Ralph E. Meyers, Park Forest, Ill., assignors to Pullman-Standard Car Manufacturing Company, Chicago, Ill., a corporation of Delaware

Application March 7, 1952, Serial No. 18,819

Term of patent 14 years

(Cl. D66—1)

To all whom it may concern:

Be it known that we, Alfred B. Girardy, Donald W. Doman, and Ralph E. Meyers, citizens of the United States of America, and residents, respectively, of Park Forest, county of Cook and State of Illinois; Harvey, county of Cook and State of Illinois; and Park Forest, county of Cook and State of Illinois, have invented a new, original, and ornamental Design for a Railway Observation Car Body, of which the following is a specification, reference being had to the accompanying drawings, forming part thereof.

In the drawings:

Fig. 1 is a side elevational view of our new design for a railway observation car body;

Fig. 2 is a plan view of the car body, with portions broken away;

Fig. 3 is a cross sectional contour view taken on the line 3—3 of Fig. 2;

Fig. 4 is an end top perspective view thereof;

Fig. 5 is a perspective side view of the rear end portion of the car body; and

Fig. 6 also is a perspective view of the rear end portion thereof.

The dotted line representation of a portion of the car body indicates unessential features of the design, and the dotted line representation of the supporting trucks and attaching means is for illustrative purposes only.

What is claimed is:

The ornamental design for a railway observation car body, substantially as shown and described.

ALFRED B. GIRARDY.
DONALD W. DOMAN.
RALPH E. MEYERS.
